United States Patent Office.

ISAAC KLING, OF SEYMOUR, INDIANA.

Letters Patent No. 79,233, dated June 23, 1868.

IMPROVEMENT IN BILLIARD-REGISTERS.

The Schedule referred to in these Letters Patent and making part of the same.

TO ALL WHOM IT MAY CONCERN:

Be it known that I, ISAAC KLING, of Seymour, in the county of Jackson, and State of Indiana, have invented certain new and useful Improvements in Automatic Billiard-Game Keeper; and I do hereby declare that the following is a full, clear, and exact description thereof, reference being had to the accompanying drawings, and to the letters of reference marked thereon, which form a part of this specification, and in which—

Figure 1 represents a vertical longitudinal section of my improved game-keeper.

Figure 2, a horizontal section of the slide-case.

Figure 3, a vertical transverse section of the slide-case, and a portion of the tube which contains the dies.

Figure 4, a section of one of the checking-points.

Figure 5, a view in perspective, and

Figure 6 a view in elevation of portions of the wires E¹ and F.

The object of my invention is to provide a simple and convenient apparatus for registering the number of games played upon a billiard-table by the movement of the points in counting the game, so that it shall be impossible for the players to mark their game without indicating to the person in charge of the table that a game has been played; and to this end my improvement consists in providing two movable slides, enclosed in a suitable case, and operated by the rod which carries the points, together with an index-rod, furnished with dies numbered to record the games, and so arranged that the movements of the slides will cause a die to be protruded from the case for every game that is played.

In the accompanying drawings, which show a convenient arrangement of parts for carrying out the objects of my invention, A represents a case or box, in which two slides, B and C, move longitudinally. The slides are placed one above the other in the case, being separated by the cross-pieces B², over which the top slide, C, moves, and which prevent the lower slide, B, from receiving any vertical movement. Suitable openings are made in the slides for the index-rods and dies to pass through.

The slide B is attached to C by a cord, b, passing over the pulleys b b¹, the other end of the slide C being connected to a spring, c, either plate, spiral, elliptic, or other convenient form, fastened to the case A. A hook, B¹, is pivoted to the end of the slide B, which is pressed down by a spring, b², attached to the slide, and engages in a notch, E², in one end of a bar, E, to the opposite end of which the wire E¹, on which the points e are strung, is secured. The hook B¹ is disconnected from the rod at the proper time by striking against the inclined plane B³ on the bottom of the case A.

A wire, E¹, on which the points e are strung, is secured to the outer end of the bar E by means of a set-screw, e¹, or in any other suitable manner. A guide-wire, F, is secured to the bottom of the slide-case, and extends outwards parallel to and immediately beneath the wire E¹. A stop, f, is placed upon the wire F, to which the points are moved to count the game. The points e have holes in them large enough for the wires E¹ and F to pass through, the points sliding upon these wires. The first point, or that with which the player commences to mark his game, is secured to the wire E¹, but not to F. The other points slide freely upon both wires. The first point being secured to the wire E¹, and this to the bar E, it will be seen that as soon as the player commences to mark his game, the movement of the first point to the stop f draws out the slide B, which movement of the slide causes a die to be protruded from the case in a manner hereinafter to be described.

To prevent the player from moving back the points at the end of the game, and marking a new game without recording that it has been played, every tenth or twentieth point, which I term a checking-point, is provided with a latch, e², and spring e³, for holding the same in a notch, e⁴, on the wire E¹. A depression, f², is made in the wire F, which enables the latch e² to slide into the notch when the point is moved up thereto.

In the position shown by figs. 1 and 2, one of these checking-points, e², stands immediately above the notch e⁴, but the latch is prevented from catching therein by the wire F, which, at the point f², immediately beneath the notch e⁴, at the commencement of the game, does not present any depression for the latch to enter. When the wire E¹ is drawn out by means of the first point, the notch e⁴ stands above the depression f² in the lower wire F, and as soon as the checking-point e² is moved up to the notch, the spring e³ forces the latch e² therein,

and the points cannot be moved back without carrying back the wire E^1 , and thereby moving the bar E a sufficient distance into the case for the hook B^1 to engage in the notch E^2 , when the slides are in readiness to protrude another die as soon as the next game begins to be marked.

The beginning of the depression f^2 is a gradual incline, which is placed in such position upon the wire F that as soon as the wire E^1 has been moved back a sufficient distance for the hook B^1 to engage in the notch E^2 , the latch c^2 strikes against the incline, which raises it out of the notch, and the full diameter of the wire F beneath it prevents it from catching in the notch again until moved up to its proper position for marking the next game. The last point is locked and prevented from being moved up too far towards the slide-case by the latch c^2 engaging in the notches c^2 and f^2 in the wires E^1 and F .

An index-rod, D , having dies, d , upon it, numbered consecutively to record the games played, moves in a vertical tube, D^1 , communicating with the slide-case, and passes through openings in the slides and bottom of the case. The dies d are made in the form of hollow square blocks, surrounding the index-rod, the lower edges of which form shoulders to rest upon the edges of the opening in the upper slide C , and upon doors, I , hinged to the lower slide B ; and are furnished with legs, d^1 , to maintain them at a sufficient distance apart for the upper slide to move between them.

To prevent the index-rod from being pushed up by the player after a game has been played, plates d^2 are hinged to the top thereof, which are pressed downwards by a spring, d^3 , and engage in notches H in the tube D^1 . Any pressure from the bottom will only tend to force the plates more firmly into the notches, and prevent the index-rod from being raised; and when it is desired to raise the index-rod for recording a new series of games, this is done by pulling down a ring, g^2 , on the end of a cord, g , attached to the plates d^2 , and passing over the pulleys g^1 to a box, G , which is accessible only by the proprietor or person in charge of the table. The opening in the slide C is a long slot, that part of which through which the index-rod passes when the slides are ungared from the bar E , or when the bar E is just beginning to act as the slide, being of sufficient width to allow the index-rod and dies to drop through, but for the remainder of its length it is only of sufficient width to admit the rod, the dies being prevented from passing through by the shoulders formed by their lower edges striking against the edges of the slot.

The width of the slot in the slide B is the same as the greatest width of that in C , and it is provided with doors I , pressed down by springs i , which, when closed, will only afford space for the rod to pass between them, the dies resting upon them in the same manner as upon the edges of the narrow part of the slot in C . When the under rod is drawn up by the cord g , the doors I swing upon their hinges and allow the dies to pass through the springs i , returning them to the horizontal position.

The operation of the machine is as follows: The index-rod is raised by the cord g , which, as before stated, is under the control of the proprietor or person in charge, until the first die rests upon the doors I . One or more of the points e being moved out to the stop f , to commence marking the game, the bar E and slide B are thereby drawn out, and the doors I being drawn away from the first die, the latter drops down outside of the case to the lower end of the index-rod, indicating one game. At the same time the narrow part of the slot in C , having passed under the second die, prevents it from falling through. When the hook B^1 is raised by the incline B^2 out of the notch E^2 , the spring e draws back the slides C and B to their first position, causing the second die to drop through the wide part of the slot in C upon the doors I , and as soon as the players commence counting the second game, the second die drops through in a similar manner.

The cross-pieces B^2 may be dispensed with, and the slides guided by grooves in the sides of the case, which latter method I prefer. The inclined plane for ungearing the hook from the notch may be also dispensed with, and a rocking-shaft and arms, operated by the slide, substituted, if deemed more convenient.

When it is desired to provide a check whereby the proprietor can verify the account of the person in charge of the tables, a similar apparatus is added for the inspection of the proprietor, having an index-rod long enough to contain sufficient dies to show the number of games played on all the tables in the course of a day, (or several rods and sets of slides in the same case,) and having its lower slide connected by cords with the lower slides of the game-keepers of the various tables. Each time that a game is marked, the cord attached to the lower slide of the game-keeper that shows it, will move the slide of the supplementary apparatus, and indicate a game. The index-rod may pass into a locked box accessible only to the proprietor, and the apparatus may be placed in any portion of the building desired.

The games can be indicated at any distance from the table by using one case containing merely a single slide, and its unhooking-gear placed at the end of the wire that carries the points, without index-rod or dies, and having its slide connected to a cord, which extends to the lower slide of an apparatus constructed in the manner described, except that the hook and disconnecting-gear are dispensed with, by which the games are indicated, as hereinbefore set forth.

It will be seen that my invention affords a simple and convenient means of recording the number of games played free from the complication of clock-work arrangements, and requiring no manipulations on the part of the players beyond those ordinarily made in playing a game.

Having thus fully described my improved automatic game-keeper, what I claim therein as new, and desire to secure by Letters Patent, is—

1. Operating the index-rod, which shows the number of games played, by the movement of the points to mark the games, as set forth.
2. The combination of the slotted slides B and C , doors I , index-rod D , and spring e with the bar E and wire E^1 , when arranged and operating substantially as described.
3. The pivoted plates d^2 and spring d^3 , in combination with the notches H , for preventing the index-rod from being raised from the outside of the case.

4. The spring b^2 and inclined plane B^3 , for operating the connection and disconnection of the slider and bar E , as set forth.
5. The checking-points e^2 , provided with springs e^4 and latches e^5 , in combination with the notch e^6 and depression f^3 , for preventing the points from being moved backwards and re-marked without counting a game, as set forth.

In testimony that I claim the foregoing as my own, I affix my signature in presence of two witnesses.

ISAAC KLING.
